UNITED STATES PATENT OFFICE

157,175

HOLLOW METAL MOLDING

Leon C. Laub, New Rochelle, N. Y.

Application November 26, 1948, Serial No. 149,834

Term of patent 7 years

(Cl. D54—2)

To all whom it may concern:

Be it known that I, Leon C. Laub, a citizen of the United States, residing at New Rochelle, in the county of Westchester and State of New York, have invented a new, original, and ornamental Design for a Hollow Metal Molding, of which the following is a specification, reference being had to the accompanying drawing, forming part thereof.

The figure is a perspective view of a hollow metal molding, showing my new design, an intermediate portion being broken away to indicate indefinite length.

I claim:

The ornamental design for a hollow metal molding, substantially as shown and described.

LEON C. LAUB.
